DOUBLE HYPODERMIC NEEDLE TYPE PILOT BURNER

Leslie F. Vixler, Rocky River, Ohio, assignor to The Patrol Valve Company, Cleveland, Ohio

Application October 27, 1955, Serial No. 543,101

5 Claims. (Cl. 158—115)

This invention relates to lighters for gas burners, such as are used on gas cooking ranges or other gaseous fuel appliances, more specifically it relates to automatic lighters, employing a low-input constantly-burning pilot burner adapted to be used independently of, or in conjunction with a flash tube construction, for causing the ignition of a fuel burner, in a well known manner.

This invention relates to a low-input pilot burner employing an hypodermic needle of the general type of pilot burner disclosed in my co-pending application, Serial No. 524,966, filed July 28, 1955.

The problem in providing low-input pilot burners operating on a B.t.u. input rating within the range of 50 to 100 B.t.u. per hour, or less, is to provide a stable pilot burner, either when disposed adjacent range burners for direct burner ignition, or when disposed at a distance from range burners and connected therewith by flash mechanisms which produce concussion waves in the flash tubes having a tendency to pull out or extinguish the pilot flame.

I have discovered that by using two hypodermic needle type pilot burners, disposed as disclosed herein, providing impinging flames, used independently of or in conjunction with a flame stabilizing wire, an exceptionally stable pilot flame is produced, which is stable and substantially unaffected by the concussion waves and drafts inherent in flash tube mechanism operating from a central pilot burner.

Therefore, an object of this invention is to provide a stable, low gaseous fuel input pilot burner adapted to operate on B.t.u. input per hour ratings on the order of 25 B.t.u.

Other objects are to provide ignition means adapted to light burners directly or through flash mechanism, the same being adapted to be disposed in either vertically upward, horizontally or vertically downward positions.

Other objects of the invention are to provide a low input pilot burner, adapted to be manufactured at a relatively low cost, which may be used with various types of gases and burners, and which may be readily installed and removed, and which is simple and reliable in operation.

These and other objects will be apparent during the course of the following specification.

In the drawings forming a part of this specification:

Fig. 1 is a top view of a gas cooking range with parts broken away, illustrating a centrally disposed pilot burner;

Fig. 2 is a side view of a range burner and my pilot burner disposed in close proximity to the range burner for direct burner ignition;

Fig. 3 is an enlarged broken sectional view of the pilot burner shown in Fig. 2, drawn to a larger scale;

Fig. 4 illustrates a range burner, a modified form of pilot burner disposed at some distance from the range burner, and associated flash tube mechanism;

Fig. 5 is an enlarged broken sectional view of the pilot burner shown in Fig. 4, while

2

Fig. 5a illustrates a central header used with the form of invention illustrated in Fig. 2.

In the drawings the numeral 10 refers to the top plate of a gaseous fuel cooking range, showing a centrally disposed pilot burner and having suitable apertures for accommodating a plurality of range burners 11, supplied with fuel from a supply pipe or manifold 12 through Bunsen tubes 13, the flow of gas from the manifold 12 being controlled by individual valves 14, in a well known manner. A pilot burner may be disposed in close proximity to each range burner for direct ignition action, as illustrated in Fig. 2, or it may be centrally disposed between the range burners and operatively connected to the individual range burners by flash mechanism as illustrated in Fig. 4.

The pilot burner 15 illustrated in Figs. 2 and 3 comprises two parallel thin elongated pilot burner tubes 16 in the general form of hypodermic needles, preferably made from hypodermic needle tubing, and suitably fabricated from a ferritic type of stainless steel, the sizes generally used being in the range of 16 gauge (.065" O.D. x .009" wall) to 26 gauge (.018" O.D. x .04" wall). The inner ends of each pair of pilot burner tubes 16 are disposed at the end of a pilot gas tube 17 receiving gas from a central header 18, suitably supported centrally of the range top 11, and supplied with fuel through tube 19 from the gas manifold 12, while a regulating valve 20 controls the flow of gas from the manifold 12 to the supply tube 19. A retaining nut 21 forms a closure or support member internally threaded at its lower end, where it is mounted on cooperating threads on the end of gas supply tube 17, and is provided with two vertical bores 21a receiving the inner ends of pilot burner tubes 16, and retains them in fixed position. A small vertically extending nichrome flame stabilizing wire 22, usually having a diameter of .013" to .030", is disposed between each pair of pilot burner tubes 16 and is axially aligned with the axis of the pilot gas tube 17. The outer ends of the pilot burner tubes or needles 16 are inwardly tapered as indicated at 23 with the tapered surfaces disposed opposite each other.

The foregoing structure is adapted to directly ignite range burner 11 without the use of flash tube mechanism, said burners 11 being mounted on the end of Bunsen tubes 13 and retained thereon by a bayonet locking means 26. A tower or stack 27, is provided for carrying the igniting flame from the pilot burner 15 up to the burner ports 25, the stack 27 being provided with a flash slot 28 leading to a flash tip 29 at the top thereof, and an ignition port 33 intermediate to the top and bottom of the stack 27, the flow of gas from the Bunsen tube 13 to the tower 27 being through extension tube 30.

Figs. 1 and 4 illustrate the use of my double hypodermic needle type of pilot burner at considerable distance from the range burners, usually one constantly burning pilot burner being disposed centrally of the range top, while flash tube mechanism operatively connects each range burner to the central pilot burners. My pilot burner is especially useful for this type of flash tube ignition, from a central pilot, as its flame stability is such, that normally it is virtually unaffected by the flash or concussion of the ignition.

In this form of the invention I illustrate similar range burners 11, having ports 25, secured to the end of Bunsen tubes 13 by a bayonet locking device 26, and a tower having flash slot 28, flash tip 29, and an ignition port 33 having an igniting flame 33a illustrated in the drawing. A support bracket 31 suitably secured to the range structure supports pilot gas tube 17, as shown in Fig. 2, and supports flash tube structure 32 having its inner ends retained in a pilot burner housing 24, as shown in Fig.

4. In this embodiment of the invention the hypodermic pilot burner 15a, suitably supported and disposed centrally of the range top 11, comprises two hypodermic needles 16a receiving gas through pilot tube 19 and having their outer ends reversely bent and disposed towards each other, while a flame stabilizing wire 22a, disposed between each pair of pilot burner needles 16a, provides a feature, whereby once the pilot burner is lighted, the wire 22a glows red, serving as a readily discernible means indicating that the burner is ignited, and also assures rapid ignition of the cold gases as they emerge from the pilot burner, thus enabling the pilot to operate on a substantially lower B.t.u. input than otherwise would be possible.

For certain uses it may not be necessary to use the flame stabilizing wire 22a and such construction is within the contemplated scope of my invention. The disposition and arrangement of the pilot burners 16 and 16a is such, that a single flame is produced by the coalescing of the two flames at each pair of hypodermic needle ends, forming a relatively flat flame pattern indicated by the letter F in the drawing.

When the pilot burner 15 is located adjacent the range burner 11, as shown in Figs. 2 and 3, upon operating a valve 14, gas passes through an associated Bunsen tube 13 to a cooperating range burner 11, while a small volume of such gas passing through extension tube 30, becomes ignited at the ignition port 33 by the flame at the pilot burner 15, the flash flame then travels up the flash slot 28 to the flash tip 29 disposed in close proximity to the main burner 11, and ignites it, as is well known in the art.

The operation of the embodiment of the invention illustrated in Figs. 4 and 5 is quite similar to that described for Figs. 2 and 3, except that flash tube mechanism 32 is interposed between the tower 27 and the pilot burner 15a, to conduct the raw gas from the Bunsen tube 13 to the pilot burner 15a, where it is ignited by the pilot flame, flashes back to the ignition port 33 and then passes upwardly in the tower 27 to light the range burner 11, as previously described.

The exceptionally low gas input feature of the pilot burner disclosed herein, when applied to a gas cooking range, permits the use of a separate pilot burner for each of the four range burners commonly provided on ranges, the total gas input for such four individual pilot burners being substantially less than the gas input required for a single conventional pilot burner used to ignite the same number of burners through flash mechanism.

It is believed that by using two or more small pilot burner tubes, positioned and arranged in such manner that the resultant flames impinge one upon the other, a very stable flame is produced, due to the stabilizing influence of one flame on the other. By adding a flame stabilizing wire between the two flames, a filament type of pilot burner is produced. Once the pilot burners are ignited, the flame stabilizing wire glows red, thus providing means for rapid ignition of the cool gases as they emerge from the pilot burner.

It will be apparent to those skilled in the art that the present embodiment of the invention is illustrative only and that the invention may be variously changed, used or modified without departing from the spirit of the invention or sacrificing the advantages thereof.

I claim:

1. A pilot lighter device comprising, a pair of spaced vertically extending gas tubes disposed in parallel relation to each other and fluidly connected to a source of gas at their lower ends, said tubes being formed of relatively thin-wall tubing having an outside diameter approximately within the range of .065" to .018", having an inside diameter approximately within the range of .047" to .010" and having fine upwardly directed axial ports at their upper ends, said tubes being separated

5 by a distance approximating three times the diameter of said tubes.

2. A pilot lighter device comprising, a pair of spaced vertically extending gas tubes disposed in parallel relation to each other, separated by a distance corresponding to three times the outside diameter of said tubes and fluidly connected to a source of gas at their lower ends, said tubes being formed of relatively thin-wall tubing having an outside diameter approximately within the range of .065" to .018", having an inside diameter approximately within the range of .047" to .010" and having fine upwardly directed axial ports at their upper ends, and an upwardly projecting flame stabilizing wire having a diameter within the range of .013" to .030" disposed midway between said tubes, disposed in the same plane thereof and extending to at least the top margins of said tubes but not more than six times the outside diameter of the tubes above that margin, thereby providing a single flame surrounding said wire and ports.

3. A pilot burner device comprising, a plurality of spaced vertically extending gas supply tubes having inside and outside diameters as stated in claim 2 disposed in parallel relation to each other, said tubes being in fluid communication with a gas supply at their lower ends, the upper end portion of each tube being bent over forming a downwardly projecting portion, spaced a relatively short distance from each vertical tube portion and extending downwardly therefrom a relatively short distance in parallel relation thereto, said bent over portions being directed toward each other and provided with relatively small diameter downwardly-directed burner ports at their lower ends, the distance between said burner ports being such that a single low-input stabilized flame is produced around said ports and the area therebetween.

4. A pilot burner device comprising, a pair of vertically projecting parallel disposed gas supply tubes of uniform diameter, having an outside diameter substantially within the range of .065" to .018" and having an inside diameter approximately within the range of .047" to .010", connected to a source of gas at their lower ends, said tubes being spaced apart a distance corresponding to six to eight times the diameter of said tubes, the upper end portion of each tube being bent over forming a downwardly projecting portion spaced from the vertical tube portion by a distance corresponding approximately to twice the diameter of the tube, said downwardly projecting portion extending downwardly from the top portion of the tube in parallel relation thereto a distance corresponding to approximately two to three times the diameter of said tube, said bent over portions being directed toward each other, and provided with fine downwardly-directed burner ports at their lower ends, for the purposes described.

5. A pilot burner device comprising, a pair of vertically projecting parallel disposed gas supply tubes, having an outside diameter substantially within the range of .065" to .018" and having an inside diameter approximately within the range of .047" to .010", connected to a source of gas at their lower ends, said tubes being spaced apart a distance corresponding to six to eight times the diameter of said tubes, the upper end portion of each tube being bent over forming a downwardly projecting portion spaced from the vertical tube portion by a distance corresponding approximately to twice the diameter of the tube, said downwardly projecting portion extending downwardly from the top portion of the tube in parallel relation thereto, a distance corresponding to approximately two to three times the diameter of said tube, said bent over portions being directed toward each other and disposed in the same plane, and provided with fine downwardly-directed burner ports at their lower ends, and an upwardly projecting flame stabilizing wire, having a diameter within the range of .013" to .030" disposed midway between said pair of tubes in parallel relation thereto and extending at least to the top portions of said tubes, whereby a single

stabilized low-input flame is produced surrounding said wire and said tube ports.
